ULTRA HIGH FREQUENCY AMPLIFIER
SYSTEMOrville E. Dow, Port Jefferson, N. Y., assignor to
Radio Corporation of America, a corporation
of Delaware

Application June 30, 1939, Serial No. 282,117

16 Claims. (Cl. 250—27)

This invention relates to an ultra high frequency amplifier suitable for use on frequencies of the order of 500 megacycles, though not limited thereto, and particularly concerns the constructional and mechanical details of the circuit elements which go to make up such an amplifier.

The invention has for one of its objects to provide a construction for ultra high frequency operation which allows the interchange of units or the inspection thereof to be easily effected, and in which the lengths of connections are reduced to a minimum.

The invention also relates to novel tuning arrangements for tuning the filament leads of electron discharge devices; also to novel neutralizing condensers for the amplifier vacuum tubes; and to novel adjustable condensers movable over the input and output transmission line circuits.

A feature of the invention lies in the use of a novel mechanical construction for the tuning condensers for the input and output circuit leads, wherein sliding contacts between elements of the condenser are wholly avoided. By means of this type of condenser, there is obtained a wide range of tuning with a fine adjustment of the circuit.

Another feature resides in a particular type of concentric neutralizing condenser which has an absolute minimum of lead inductance and small capacity, and which is adjustable over a considerable range. This novel construction is easily removable and facilitates changing of amplifier electron discharge devices.

A still further feature is the transposition block arrangement employed for transposing the grid and anode leads from a vertical plane in the vacuum tube compartment to a horizontal plane required in the shielded rear compartment which accommodates the input and output leads.

Still further features of the invention relate to the condenser arrangement used to series tune the filament leads so that the active part of the filament has an extremely low impedance to ground; to the filament concentric line circuit for offering a high impedance to radio frequency currents flowing from the filament to ground and low impedance for filament heating current; and to the arrangement of panels and shields which enable the prongs of the vacuum tubes to be mounted through the walls of the panels, thus minimizing lead lengths and insuring perfect shielding.

The novel constructional arrangement of the invention, as herein described, has been successfully used in a relay transmitter for amplifying 500 megacycle signals, although it will be under-

stood that the various elements thereof as well as the circuit as a whole may be used in a receiver and in other arrangements.

A more detailed description of the invention follows in conjunction with the drawings, wherein:

Fig. 1 shows a schematic diagram of an ultra high frequency amplifier comprising a pair of electron discharge device amplifiers connected in push-pull relationship and mounted generally in accordance with the principles of the invention;

Fig. 2 is a front view of the vacuum tube compartment showing some of the novel constructional details involved in mounting the pair of tubes;

Fig. 3 is a rear view of the ultra high frequency amplifier construction embodying the principles of the present invention, showing the input and output leads as they are mounted in their shielded respective compartments;

Fig. 4 shows a side section of Fig. 3 and illustrates in part a side view of the exterior of the vacuum tube compartment;

Fig. 5 is a detail showing the transposition block which is employed in the construction of the circuit arrangement;

Fig. 6 is a section on line 6—6 of Fig. 5;

Fig. 7 shows a front view of the transposition block of Fig. 5 with the vacuum tube compartment and the shielded paneling between this compartment and the rear compartment removed, in order to show very generally how the input and output leads pass through the transposition block;

Fig. 8 is a cross-sectional view of one of the neutralizing condensers employed in the present invention between the anode of one vacuum tube and the grid of the other vacuum tube;

Fig. 9 is a section of the filament concentric line showing the details thereof and the manner in which tuning of the vacuum tube filament leads is accomplished; and

Fig. 10 is an enlarged view of a portion of the filament concentric line of Fig. 9 showing in more detail the manner in which the filament heater leads are disposed within the interior of the inner conductor of the filament concentric line and the way they connect to the elements of the filament tuning condenser.

Throughout the drawings, the same reference numerals indicate the same parts.

Referring to the drawings and to Fig. 1 in particular, which shows schematically the entire circuit arrangement of the ultra high frequency amplifier of the invention, there are shown a

pair of amplifier triode vacuum tubes 101, 101 mounted inversely with respect to each other. The two terminals for each of the anode and grid electrodes of these electron discharge devices extend from the envelope in opposite directions, so as to minimize lead connections, while the filament leads of each vacuum tube extend through one end of the envelope, as shown. The general configuration of these vacuum tubes are shown in more detail in Fig. 2, which will be described later. The anode and grid terminals of the vacuum tubes 101, 101 extending in one direction make direct contact with terminals 109', which extend through transposition block 109 shown and described in more detail later in connection with Figs. 3, 4, 5 and 6, while the anode and grid terminals which extend in an opposite direction make contact with neutralizing condensers 110, 110. Condensers 110, 110 effect cross-neutralization of the amplifier circuit and are of concentric line type of construction, each of which is tunable by means of a knob 227. The input energy is supplied from a loop 105, in turn coupled to input leads 103 which are short circuited at one end by a strip 120 and connected at the other end to the grids of the vacuum tubes 101, 101. Output energy from the vacuum tubes is taken by the output leads 104 which are connected at one end to the anodes of the vacuum tubes 101, 101 and short circuited at their other ends by a short circuiting strap 121. Energy is derived from the output leads 104 by means of a loop 106 which is arranged parallel to and spaced from leads 104. The conductors 103, 104, 105 and 106 are preferably made of copper rod or tubing. Both the input and output leads 103 and 104, respectively, are each electrically substantially three-quarters of a wavelength long at the carrier or operating frequency (when above 300 megacycles), as measured from the short circuiting strap to the vacuum tube grid and anode electrodes. Across the input and output leads 103 and 104 there are provided balanced type tuning condensers 107 which are movable by means of a dial arrangement 113 over the lengths of these input and output leads. Condensers 107 are variable and serve to tune the input and output circuits. Across the first voltage nodal point on the output circuit, which is immediately outside the transposition block, there is provided a shunt inductance 108 to discourage oscillations at a lower frequency than the operating frequency. Putting it another way, the shunt inductance strap 108 prevents the amplifier from oscillating at a lower frequency than the carrier or operating frequency. Suitable grid bias for the vacuum tube amplifiers is obtained by means of grid bias resistors 122 connected to the lower end of the input leads 103. The short circuiting strap 120 provides a path of extremely low impedance for energy of the operating frequency between the legs of the input leads 103. By-pass condensers 123 serve to provide a blocking path for direct current between the legs of the input leads. A suitable positive potential is applied to the anodes of the vacuum tubes by means of a lead 124 which extends from the positive terminal of the source of potential, here indicated by the positive sign (+), to the mid-point of strap 121 across the output leads 104. The filament circuit for each of the vacuum tubes 101, 101 comprises a concentric conductor transmission line having an outer grounded conductor 125 and an inner conductor 126, and a two-plate variable condenser

114, one plate of which comprises the plurality of by-pass condensers 116, while the other plate is an adjustable stud or disc 129 mounted on the side of the vacuum tube compartment as shown 5 in more detail in Fig. 2. The filaments of the vacuum tubes are adjusted to be at zero radio frequency potential by means of variable condenser 114. Thus all the R. F. current which flows in the filament leads flows to ground 10 through condenser 114. The inner conductor 126 of the filament concentric conductor line is approximately one-quarter of a wavelength long and shorted for R. F. at its far end and offers 15 a high impedance to the radio frequency currents flowing from the filament to ground. The heater leads for the filament extend inside of the inner conductor 126. The condenser 114 serves mainly to series tune the filament internal leads (i. e., internal in the vacuum tube) so that the 20 active part of the filament has a low impedance path to ground. In effect, the filament concentric line is a choke which serves not only as a high impedance for the radio frequency energy, but also supplies heating power to the filament 25 and a path to ground for the D. C. emission current.

The neutralizing condensers 110, 110 are adjusted so that the capacitive resistance from the anode of one vacuum tube to the grid of the 30 other vacuum tube is equal to the reactance of the grid to anode capacitance of the tube. This adjustment takes into account the series inductance of the leads to the neutralizing condensers. Due to the appreciable inductive reactance of 35 the leads connecting the neutralizing condenser to the tube electrodes, the capacitance of the neutralizing condenser will be considerably less than the grid to anode capacitance of the vacuum tube. This requires that the neutralizing condensers have an absolute minimum of lead 40 inductance and that the capacity be small but adjustable over a considerable range. These neutralizing condensers, as shown in more detail in Fig. 8, meet these desired requirements, and 45 in addition have the advantage of being easily removable from the vacuum tube compartment, thereby facilitating the change of vacuum tubes.

From what has been said above, it is believed 50 that the general operation of the push-pull vacuum tube amplifier arrangement of Fig. 1 will be obvious to those skilled in the art from a mere inspection of the circuit diagram.

Fig. 2 shows in more detail the mechanical constructional details of the vacuum tube 55 mounting with the neutralizing condensers and certain of the filament tuning condensers. Each vacuum tube 101 has an anode prong and a grid prong, designated respectively A and G, extending from opposite sides of the envelope, although 60 it will be appreciated that in Fig. 2 there is shown only one side of each of these vacuum tubes. The tubes 101, 101 are inverted with respect to each other so that the lengths of the leads to the neutralizing condensers will be a minimum. These neutralizing condensers which 65 have been designated 110 in Fig. 1 are here designated by the reference numerals 221, 222, 223, and 224, which are the same references employed in the more detailed description of these neutralizing condensers given in connection with Fig. 8. At this time it is believed to be sufficient 70 for an understanding of this Fig. 2 to point out that elements 221 and 222 are metal cylinders which are mounted on a quartz rod 224 and that 75 the capacity is adjustable by means of a rotat-

able disc 227 fastened to a shaft 229 which controls the adjustment of the condenser.

The tuned heater leads for each filament, as well as the central lead from the mid-point of the active element of the filament, are brought out at one end into small metallic plates 127 to which they are securely attached by means of screws 128. These plates 127 are insulated from each other. The two outer leads or heater leads are connected through their associated plates 127 to leads in the interior of the inner conductor 126 of the filament concentric line. The central plate 127 is connected directly to the nearest end of the inner conductor 126 and to the two encasing plates of 116, as shown in more detail in Fig. 10. These three plates 127, 127 form bypass condensers labeled generally 116, which bypass condensers form a capacity with an adjustable disc or stud 129 which is movable by means of a screw and knob 130 from the exterior of the vacuum tube compartment, as shown in more detail in Fig. 9. It should be observed that the plates 127, 127 extend through an aperture in the bottom (or top) of the vacuum tube compartment and through a hole in the outer conductor 125 of the filament concentric line to the inner conductor. By adjusting knob 130 to vary the tuning condenser 114, we are thus able to series tune the filament internal leads, so as to place the active part of the filament in the vacuum tube at ground potential. Similar constructions of filament concentric lines and tuning condensers are employed for both vacuum tubes.

Fig. 3 shows the mechanical details of the rear compartment of the ultra high frequency amplifier, and illustrates the manner in which the input and output leads and their associated elements are all mounted in a grounded metallic box 102. It should be observed that the walls of all compartments are made of metal, and that the input and output leads are shielded from each other by a metallic U-shaped bracket 131 mounted externally of the transposition block 109. It should be noted that inductance 108 takes the form of a short section of concentric line which passes through the U-shaped shield 131. The concentric conductor line serves to shield 108 from the input circuit, and passes through 131 as the most direct path between the voltage nodal points on the conductors 104, 104. The short circuiting straps 120 and 121 are actually metallic plates bridged across the legs of the input and output leads, it being evident, of course, that short circuiting strap 120 is separated from each of the legs 103 by means of mica spacers 132 in order to form the radio frequency by-pass direct current blocking condensers 123. At each end of box 102 is a small metallic box 115 for accommodating the input coupling loop 105 or the output coupling loop 106. If desired, ventilating or cooling air can be blown through one of the boxes 115 and up through the box 102 and out through the other box 115 in the direction of the arrows, as shown in Fig. 4.

The construction of the condenser 107 is clearly shown in Fig. 3 taken in conjunction with Fig. 4 and will now be described in detail. The condenser 107 comprises a metallic block 333 which has two apertures extending therein through which the leads 103 or 104 extend (note Fig. 4). The block 333 has the function of the rotor of the conventional balanced condenser and the size of the holes therein permit it to pass freely over sleeves 332 without touching

them. Sleeves 332 each have one slot extending the whole length thereof. The block 333 is supported by insulators 334, the latter being mounted on a plate 336 to which is secured the rack 335. A pinion 337 on a shaft 338 of a tuning dial 113 engages the rack 335 and causes the plate 336 with insulators 334 and block 333 to move up or down, and thereby increase or decrease the resonant frequency of the circuit 103 or 104. The ratio of diameters of the holes in block 333 to the outside diameter of the sleeves 332 and the length of the sleeves 332 and the block 333 determines the maximum capacity. The condenser can be used without the sleeves 332 but their use results in a greater change in the resonant frequency for a given movement of block 333. Generally, the sleeve 332 will be placed near the voltage maximum point on the input or output leads. These sleeves 332 in effect increase the cross section of the conductors of the input and output circuits at or near a voltage loop, thus increasing the maximum capacity obtainable. Since the sleeves are movable, this maximum capacity may always be located at the voltage loop. This type of condenser has the advantage of totally avoiding the use of sliding contacts, and of giving a wide range of adjustment. This wide range of tuning will be evident when it is considered that with the block at the extreme position at the input or output conductors, that is at a voltage nodal point, the condenser acts to increase the resonant frequency above that of the circuit alone. As the block 333 is moved toward the free ends of the input or output leads, that is, away from the short circuited ends, the resonant frequency decreases and is a minimum when the block 333 is at the voltage maximum point. The block 333 has been supported on insulators 334 merely for convenience, but these insulators are not necessary since the block is at ground or zero radio frequency potential. If the gap between the block 333 and the sleeve 332 is large enough to withstand the peak radio frequency voltage on the input or output leads, the block may be supported by metal posts. It will also be understood that other mechanical means of moving block 333 may be used than that shown and described.

Figs. 5 and 6 show the transposition block 109 in more detail. This transposition block is made of metal and contains, in effect, four slanting apertures, each of which has a half ledge 133. The holes which extend through the transposition block are on a straight line through the center of the largest face of the block. This transposition block serves to transpose the relative position of grid leads and anode leads from the vertical plane in the vacuum tube compartment to the horizontal plane required in the rear circuit compartment for connecting to the input and output circuits 103 and 104, respectively. This transposition block is shown also in Fig. 7 with the tube compartments broken away and with the wall between the vacuum tube compartment and the rear compartment also removed, in order to show how the prong holding the clips on the transposition block connect with the input and output leads. The vacuum tubes are shown in dot and dash lines in order to indicate the relative positions they take when mounted in the tube compartment. The R. F. circuit is not connected to the metal transposition block electrically or supported from it by insulators. The transposition block shields the four leads which go through it from each other. The sockets

or clips for the anode and grid tube prongs are supported from the circuits 104 and 103. The rod attached to 104 (or 103) which goes through the hole in the transposition block supports rigidly two spaced flat spring strips (of good electrical conductivity such as beryllium copper). On the other end of these spring strips is supported the drilled and slotted bronze rod which receives the tube prong. The screw which is tapped into this tube prong receptacle has generous clearance in the spring strips so that the receptacle is free to move slightly to prevent putting a strain on the tube prong seal. The spring strips are normally sprung apart. The screw tapped into the tube prong receptacle draws the strips nearly together thereby assuring good electrical contact at this point.

Fig. 8 shows, in detail, the construction of the neutralizing condensers. Each neutralizing condenser comprises metal cylinders 221 and 222, to which are connected clips for accommodating the anode and grid prongs, respectively, from the vacuum tube. These anode and grid prongs are labeled A and G. Both metal cylinders 221 and 222 are mounted on a rod 224 of quartz or other suitable insulating material. Telescoping over cylinder 221 is a thin metallic sleeve 223 which is movable by means of a rod 225 of isolantite or other suitable material. Sleeve 223 is slotted so as to make good electrical contact with cylinder 221. As the sleeve 223 is moved toward cylinder 222, the capacity of the neutralizing condenser is increased. The quartz rod 224 is supported from a metallic disc 226 which in turn is fitted with a breech lock which secures it to the side wall of the vacuum tube compartment. A rotatable disc 227 is provided which is fastened to the internally threaded sleeve 228 by means of a set screw 230. Sleeve 228 is prevented from moving lengthwise by a flange 231. Sleeve 228 engages the threaded shaft 229 which is cemented to the isolantite rod 225. Thus by moving the disc 227, the isolantite rod 225 is made to move lengthwise and vary the capacitance of the neutralizing condenser. Although movement of the rod 225 may cause metallic sleeve 223 to telescope sleeve 222, so as to cause an increased capacitance between 222 and 223, in the particular arrangement successfully tried out in practice for 500 megacycles, it was not necessary to have cylinder 223 extend over cylinder 222, there being sufficient capacity obtained for the purpose of the embodiment merely by having the end of cylinder 223 come close to the end of cylinder 222 without any overlapping therebetween.

Figs. 9 and 10 illustrate in some detail the construction of the filament concentric line 125, 126 and the manner in which filament leads extend to the inner conductor. The filament leads are shown terminated at their ends with a small metallic terminal 134 which extends into holes in the plates 127. All three plates 127, 127 have an aperture therein for permitting the inner conductor 126 of the concentric line to pass therethrough. The outer plates 127, however, to which the heater leads from the vacuum tube are connected, have apertures which are larger than the inner conductor 126 of the filament concentric line. The central metallic plate 127, however, provides a close fit for the inner conductor and makes contact therewith, thus being directly connected to the inner conductor. The heater wires which extend to a source of external heater sup-

ply energy (not shown) are positioned within the interior of the inner conductor 126 and make contact with the two outer plates 127 for supplying heater energy to the filament of the vacuum tube. Since all three plates 127, 127 are insulated from each other and are sandwiched between other metallic plates from which the plates connected to the heater leads are insulated, it will be obvious that the plates 127 form by-pass condensers which are low impedance paths to radio frequency potential. The heater leads in the interior of the inner conductor 126 extend from the inner conductor to an enlarged metallic box 136 at the opposite end of the filament concentric line, in which box are terminals and by-pass condensers for the heater supply energy. The end of the inner conductor which is at the filament box 136 is provided with flanges 137 which are insulated by means of mica spacers 138 from the filament box and the outer grounded conductor of the line. A connection from the flange 137 which is the D. C. path to ground for the filament center tap is indicated as 140. Thus the D. C. ground path is through the meters shown in Fig. 1. The by-pass condensers in box 136 for the heater leads act as additional filtering means on the heater supply leads to reduce stray radio frequency fields outside the amplifier. These flanges form by-pass condensers and are in effect a short circuiting path for radio frequency energy. The inner conductor 126 of the filament concentric line 125, 126 is made to be approximately one-quarter wavelength long so as to offer a high impedance to radio frequency currents flowing from the filament to ground through the branch circuit for the filament heating current and emission current. The filament terminal block comprising the by-pass condensers 116, including the plates 127, are so made that they can be elevated to clear the filament leads 134, thus enabling the change of the vacuum tubes when necessary. A threaded screw end-plate 135 serves to provide access to the end of the filament concentric line adjacent the filament terminal block.

In the operation of the filament concentric line circuit, it will be evident from what has been said above that the D. C. ground for the filaments is through the meters shown in Fig. 1. The R. F. currents in the filament leads (heater and center tap) flow to ground through the condenser 114 and are prevented from flowing to ground by way of the concentric line 126 because it is one-quarter wavelength long and grounded at the far end by condenser 137. The capacity of 114 is between stud 129 and the outside plate of 116. Both outside plates of 116 are conductively connected to the middle plate (filament center tap) 127 at the inner conductor 126 and also by screws which hold the assembly 116 together. Thus, the R. F. current in the filament center tap lead flows directly to the outside plates of 116 and then to ground through 114. The R. F. currents in the heater leads flow through by-pass condensers of 116 to the outside plates and then to ground through 114. Thus all the filament leads are grounded by means of by-pass condensers in 116 and series tuning condenser 114. The purpose of by-pass condenser 137 is to tie one end of the inner conductor 126 to ground so that the other end offers high impedance to R. F. currents.

It should be understood that the invention is not limited to the precise arrangements indicated since modifications may be made without departing from the spirit and scope of the invention.

For example, the amplifier system may be operated without the filament center tap connection. The center tap offers a low loss path for the R. F. currents in the filament. However, if the vacuum tubes had no filament center tap the middle plate 127 would be omitted. The path from filament to ground for D. C. currents would then be obtained by a connection from ground to the center-tap of the filament heating transformer or to a center tapped resistor connected across the heater supply terminals.

What is claimed is:

1. An ultra high frequency amplifier comprising a vacuum tube having a filament, a connection from the center of said filament to a point of zero radio frequency potential, and means associated with said connection for series tuning the reactance between the center of said filament and said point to provide a path of low impedance to radio frequency energy.

2. An ultra high frequency amplifier comprising a vacuum tube having a filament, a connection from the center of said filament to a point of zero radio frequency potential, and means associated with said connection for series tuning the reactance between the center of said filament and said point to provide a low impedance path to radio frequency energy, a concentric line having inner and outer conductors and effectively one-quarter of a wavelength long at the operating frequency, and heater leads for said filament located within the inner conductor of said line and extending substantially the entire length of said inner conductor.

3. An ultra high frequency amplifier comprising a vacuum tube having a filament, heater leads for said filament and a lead for the middle point of said filament, all of said leads extending out from one end of said vacuum tube, individual metallic plates for said leads, said plates being located externally of said tube and insulated from each other for providing a low impedance capacitive coupling therebetween, and adjustable means for capacitively coupling said plates to a point of zero radio frequency potential.

4. An ultra high frequency amplifier comprising a vacuum tube having a filament, a connection from the center of said filament to a point of zero radio frequency potential, and means associated with said connection for series tuning the reactance between the center of said filament and said point to provide a path of low impedance to radio frequency energy, a concentric line having inner and outer conductors and effectively one-quarter of a wavelength long at the operating frequency, and heater leads for said filament located within the inner conductor of said line and extending substantially the entire length of said inner conductor, said heater leads being capacitively coupled to the outer conductor of said line at the end of said line farthest away from said filament.

5. An electron discharge device having a filament, leads for said filament, a direct current connection from the center of said filament to a point of fixed alternating current potential, means external of said device for capacitively coupling said leads and connection together, and additional means capacitively coupling said first means to said point of fixed alternating current potential.

6. An electron discharge device having a filament, leads for said filament, a connection from the center of said filament to a point of fixed alternating current potential, terminal plates lo-

cated externally of said device for said leads and connection, and a metallic element spaced from said plates for capacitively coupling said plates to said point of fixed alternating current potential, said element being adjustable in position for varying the spacing between it and said plates.

7. An electron discharge device having a filament, a lead for said filament, means for overcoming the effect of the reactance of said lead comprising a variable capacitor located externally of said device and coupling said lead to a point of fixed alternating current potential, the effective value of said capacitor being such that there is obtained a series resonant condition thereby providing a low impedance path to said point from the active part of said filament.

8. An electron discharge device having a filament, heater leads for said filament extending externally of said device, means associated with said heater leads offering a high impedance to radio frequency currents flowing from said filament and a low impedance to heating current, a connection from said means to the middle point of said filament, and means associated with said leads and connection for tuning the same so that the active part of said filament has a low impedance path to ground.

9. An electron discharge device having a filament, heater leads for said filament and a lead for the middle point of said filament, all of said leads extending out from one end of said vacuum tube, individual metallic plates for said leads, said plates being located externally of said tube and insulated from each other for providing a low impedance capacitive coupling therebetween, adjustable means for capacitively coupling said plates to a point of zero radio frequency potential, a concentric line having hollow inner and outer conductors effectively an odd multiple of one quarter of the length of the operating wave and coupled together at one end through a low impedance path, connections extending through the interior of said inner conductor and connecting a source of heating energy to those plates associated with said heater leads, a direct current connection from said inner conductor to ground at said one end of said concentric line, and a direct current connection from the free end of said inner conductor to that plate which is in circuit with the middle point of said filament.

10. An electron discharge device having a filament, heater leads for said filament, a concentric line having hollow inner and outer conductors and effectively an odd multiple of one-quarter of the length of the operating wave, said inner and outer conductors being coupled together at one end through a path of low impedance to radio frequency energy, and a direct current connection from said outer conductor to a point of fixed alternating current potential, said heater leads extending the entire length of said inner conductor within the interior thereof.

11. High frequency apparatus having, in combination, an electron discharge device, a filament for said device, a source of heating current for said filament, leads extending from both legs of said filament to said source, a tubular conductor surrounding said leads, a lead extending from the mid point of said filament to the nearest end of said tubular conductor, means for capacitively coupling all of said leads together at said end, and a direct current connection from the other end of said tubular conductor to ground.

12. High frequency apparatus having, in combination, an electron discharge device, a filament

for said device, a source of heating current for said filament, leads extending from both legs of said filament to said source, a tubular conductor surrounding said leads, a direct current connection extending from the mid point of said filament to the nearest end of said tubular conductor, means at said end of said tubular conductor for capacitively coupling said filament leads and said direct current connection together, a direct current connection from the other end of said tubular conductor to ground, and means at said last end for capacitively coupling said filament leads to ground.

13. High frequency apparatus having, in combination, an electron discharge device, a filament for said device, a source of heating current for said filament, leads extending from both legs of said filament to said source, a tubular conductor surrounding said leads, a lead extending from the midpoint of said filament to the nearest end of said tubular conductor, means for capacitively coupling all of said leads together at said end, a variable capacitor comprising a grounded metallic element spaced from said last means and adjustably positioned with respect thereto, and a direct current connection from the other end of said tubular conductor to ground.

14. An electron discharge device having a filament and heating leads therefor, said leads having inductive reactance at the operating fre-

quency, and capacitive means connected between a surface of zero radio frequency potential and a point on said leads, said capacitive means having such value as to form a series resonant circuit between said filament and said surface for energy of the operating frequency.

15. An electron discharge device having a filament and heating leads therefor, said leads having inductive reactance at the operating frequency, capacitive means connected between a surface of zero radio frequency potential and a point on said leads, said capacitive means having such value as to form a series resonant circuit between said filament and said surface for energy of the operating frequency, and means offering a high impedance for radio frequency currents connected between said point on said leads and said surface.

16. An electron discharge device having a filament, a lead for said filament, means for overcoming the effect of the reactance of said lead comprising a capacitor located externally of said device and coupling said lead to a point of fixed alternating current potential, the effective value of said capacitor being such that there is obtained a series resonant condition thereby providing a low impedance path to said point from the active part of said filament.
